Term of patent 14 years

(Cl. D9—2)

FIG. 1

FIG. 2

FIG. 3

FIG. 4

FIG. 1 is a front perspective view of a shoe polishing machine, showing our new design.

FIG. 2 is a top plan view thereof.

FIG. 3 is an end elevational view thereof as seen from the left of FIG. 2.

FIG. 4 is a fragmentary sectional view taken substantially on the line 4—4 of FIG. 2.

The side not shown is substantially like the side shown except for the omission on the rear side of the machine of the button and knob which project to the front of the machine.

The characteristic feature of our design for a shoe polishing machine resides in the base member having the configuration shown.

We claim:

The ornamental design for a shoe polishing machine, substantially as shown and described.
